CARRIER FOR CANS

Louis R. Petrone, East Orange, and Frank W. Stevens,
Rutherford, N.J., assignors to W. R. Grace & Co., New York, N.Y., a corporation of Connecticut

Filed Jan. 27, 1964, Ser. No. 78,384

Term of patent 14 years

(Cl. D58—26)

FIG. 3.

FIG. 4.

The portions shown in broken lines are for illustrative purposes only.

We claim:

The ornamental design for a carrier for cans, as shown and described.
